UNITED STATES PATENT OFFICE.

FRANK WILCOMB, OF SAN FRANCISCO, CALIFORNIA.

NEEDLE-OPERATING CAM FOR KNITTING-MACHINES.

SPECIFICATION forming part of Letters Patent No. 350,792, dated October 12, 1886.

Application filed December 30, 1885. Serial No. 187,148. (No model.)

To all whom it may concern:

Be it known that I, FRANK WILCOMB, a citizen of the United States, residing at San Francisco, in the county of San Francisco and State 5 of California, have invented certain new and useful Improvements in Needle-Operating Cams for Knitting-Machines; and I do declare the following to be a full, clear, and exact description of the invention, such as will enable 10 others skilled in the art to which it appertains to make and use the same, reference being had to the accompanying drawings, and to the letters and figures of reference marked thereon, which form a part of this specification.

15 My invention relates to devices for operating the needles of knitting-machines.

It has been found necessary, in order to repair imperfections in the fabric, or for other reasons during the knitting, at times to push 20 the fabric backward on the needle to enable the stitches to be removed from certain needles of the series; and it is the object of my invention to afford means whereby the series of needles can be operated forward or backward 25 simultaneously, in order to provide for repairing an imperfect portion of the fabric, removing a portion of the stitches from the needles, and for narrowing or widening the fabric, and whereby to return the needles to their normal 30 position without difficulty or loss of time.

Figure 1 represents a plan view of my devices for operating needles on a straight-knitting machine. Fig. 2 represents the under side of the slide-bar L with all the parts detached. Fig. 3 represents separately the needle or stitch cams A B C attached to a plate, D. Fig. 4 represents a broken section and end view of one of the elongated grooved cams E E, with enlarged triangular mouths or 35 openings m n. Fig. 5 represents a cross-section of my device, showing the slide-bar L, cam E, slide-cam F, cap-pieces H K, and a needle, h, held in the groove g of the cam E. Fig. 6 represents the slide-cam F.

40 My invention comprises a slide-bar, L, having needle-cams A B C, arranged in the usual manner for knitting, but with enlarged triangular mouths or openings o s on each side to guide the needle-shanks into the groove X X 45 between the cams A B C.

E E are longitudinal grooved cams extending lengthwise of the slide-bar L, and having

a parallel forward and backward movement across the path of the needles, for the purpose of projecting the needles in the groove 55 forward or backward simultaneously, and having the mouth of the grooves g g, adjoining the needle-cams, enlarged and triangular in shape, as at m n, Figs. 1 and 4, for the purpose of catching and directing the needle-shanks into the grooves g g of the cams E E 60 as they pass out of the mouth o s of the groove X X of the fixed needle-cams A B C in the regular process of knitting. These longitudinal grooved cams serve to hold the needles 65 stationary or in line just before their movement, either forward or backward, to make the loops or stitches when passing through the grooves between the needle-cams.

The mouths or openings m n in the longitudinal grooved cams E E and the mouths or openings o s in the needle-cams A B C are suitably shaped and arranged to catch and direct the needle-shanks as they pass in or out of either groove either in going from right to 75 left or from left to right in the process of knitting.

The cams E E are held to the slide-bar L by the cap-plates G H J K. The sliding cam F moves in the groove in the slide-bar, and screws 80 t are inserted in the cams E E. The heads of these screws (shown in Fig. 4) move in the transverse slots u in the slide-bar L, and the shanks are in the inclined slots v in the sliding cam F, so that the movement endwise of the cam 85 F gives movement to the cams E E at right angles to the path of F. By the longitudinal movement, therefore, of the bar F the needles are simultaneously moved either forward or backward, and when the bar is stationary it 90 holds the cams in place. The needles are held from movement to the front or rear when ordinary plain knitting is being done, and they perform their usual office while passing through the grooves between the stitch-cams in the ordinary manner.

Having thus described my invention, what I claim as new, and desire to secure by Letters Patent, is—

1. The combination, in a knitting-machine, 100 with the stitch-cams having enlarged mouths, of the longitudinal cams E E, having straight grooves, as shown, also having enlarged mouths, and mechanism for operating the cams E E,

whereby the needles may be moved forward or backward simultaneously, substantially as described.

2. The combination, with a slide-bar, L, of the stitch-cams A B C, having grooves XX, formed with enlarged mouths o, the plate D, the slide-cam F, and the cap-pieces, and the longitudinal grooved cams E E, having en-

larged mouths m n adjoining the mouths of the grooves XX, all substantially as described.

In testimony whereof I affix my signature in presence of two witnesses.

FRANK WILCOMB.
